(57) **CLAIM**

The ornamental design for a steerable guiding catheter handle, as shown and described.

DESCRIPTION

FIG. 1 is a perspective view of the steerable guiding catheter handle;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof; and,

FIG. 7 is a rear elevation view thereof.

The features shown in broken lines depict environmental subject matter only and form no part of the claimed design. The subject invention is directed to the ornamental design of a steerable guiding sheath handle for use in surgical procedures.
